ALL RELAY TELEPHONE LINE CIRCUIT
AND LINE FINDER

Roy W. Jones, Rochester, N. Y., assignor to Automatic Electric Laboratories, Inc., Chicago, Ill., a corporation of Delaware

Application July 22, 1947, Serial No. 762,751

13 Claims. (Cl. 179—18)

1

The present invention relates in general to automatic telephone systems, and more particularly to improvements in automatic switching apparatus adapted for use in all-relay private automatic exchanges.

The principal object of the invention is to provide an improved linefinder designed for use in a small private automatic exchange switchboard of the all-relay type.

A further and more specific object is the provision of a simplified and economical circuit arrangement in the line equipment and call allotter, enabling a more positive and reliable operation thereof.

A feature of the invention is the provision of improved circuits for operating only one line relay at a time, such relays having one winding providing the initial operating circuit and the other winding providing the holding circuit. The holding circuit for the line relays is a chain circuit through all of the other line relays and is so designed that a line relay can lock operated only when no other line relay is operated.

Another feature is an improved marking arrangement in which the marking conductors for operating the finder tens and units relays extend direct from the line relays to the finder connect relays instead of running such conductors through the usual tens and units guard relays of the common relay distributor circuit.

Further features of the invention pertain to the particular arrangement of the circuit elements, whereby, the above and additional operating features are attained.

The novel features believed to be characteristic of the invention are set forth with particularity in the appended claims. The invention, both as to its organization and method of operation together with further objects and advantages thereof, will best be understood by reference to the specification taken in connection with the accompanying drawings in which:

Fig. 1 shows subscribers' stations such as A, B, C and D connected to lines L11, L10, L61, and L60 respectively. It shows a station's equipment such as A, more in detail and also shows the individual line equipment.

Fig. 2 shows a call allotter and a linefinder circuit.

Fig. 3 shows only the relays of a connector as necessary for the proper operation of the finder.

General description

Referring to Fig. 1, the reference characters A, B, C and D indicate subscribers' stations, with

the equipment of station A being shown in detail. The telephone at station A is connected with the system over line 11 comprising conductors 1 and 2. The line equipment individual to each station comprises line relays, such as line relays 140, 150, 160 and 170, and cut-off relays, such as relays 100, 110, 120 and 130 respectively. The line relays contain two windings, one providing their operating circuit and the other providing their holding circuit. The holding circuit for the line relays is a chain circuit through contacts of all the other line relays and is so designed that a line relay can lock operated only if no other line relays are operated. Fourth conductors such as 16 and 17 are provided through the linefinder to the associated connector to supply special services. Tens and units marking leads, such as tens marking conductors 23 and 24 and units marking conductors 21 and 22 extend from the line relays to contacts on the respective finder connect relays for controlling the operation of the finder tens and units relays.

Referring to Figs. 2 and 3, finder start relay 250 is designed to be operated by all lines having numerical designations ending in 1 through 5, and finder start relay 260 to be operated by all lines having numerical designations ending in 6 through 0. It may be assumed that there are any number of finders, the exact number being dependent on the traffic and type of service required. Only part of the last finder has been shown in detail. The connect relays such as 280, extend the tens and units marking conductors to the finder tens and units relays. Only two of the units relay group has been shown (relays 220 and 230), whereas, actually five are used. Two of the tens relay group also has been shown (relays 200 and 210), but their exact number is dependent on the number of groups of lines to be served by the equipment. If 60 lines are served, 6 tens relays are needed; while if 80 lines are served, 8 tens relays are needed. The finder is limited to serve not more than 100 lines. To provide flexibility and efficient operation, whenever the finder unit switching relay 240 of the selected finder is operated, the connection is extended through its front contact for all lines having numerical designations ending in 6 through 0. When the finder start relay 250 is operated, relay 240 is inoperative and the connection is extended by way of back contacts of relay 240 for all lines having numerical designations ending in 1 through 5. It is therefore evident that the units relays each operate an additional group of contacts (not shown) for completing a connection through either the front

or back contacts of relay 240, dependent on the last digit of the calling lines numerical designation.

Referring to Fig. 3, only the differential relay 300, the line relay 310 and the hold relay 320 of an associated connector link has been shown. Such a connector used in conjunction with this linefinder is of the type disclosed in the pending application of John H. Voss, Ser. No. 765,684, filed August 2, 1947.

Operation

The operation of the invention as to the origin of a call from any one of subscribers A through D, and the operation of the line equipment and linefinder as to finding the calling line will now be discussed.

Assuming that subscriber A of line L11 intends to place a call, the removal of his receiver completes a loop over his line conductors 1 and 2. The line relay 140 is energized through its upper winding by a circuit extending from ground through contacts 102, conductor 2, the closed loop, conductor 1, contacts 101, the upper winding of relay 140, conductor 27, contacts 253 and 264 to battery. At contacts 141, line relay 140 prepares its own locking circuit. At contacts 142, line relay 140 applies a ground potential to its incoming C conductor, thereby busying the calling line and preventing any incoming calls while the present call is being made. At contacts 143, relay 140 opens a circuit to the cut-off relay 100. At contacts 144, relay 140 prepares for the marking of the tens conductor 24. At contacts 145, relay 140 prepares for the marking of the units conductor 22. At contacts 146, relay 140 completes a circuit for energizing the finder start relay 250, this circuit extending by way of ground at contacts 146, conductor 26, the winding of relay 250 and operated contacts 272 to battery.

In operating, at X contacts 254 which close prior to the closing of its other contacts, relay 250 completes the locking circuit of the line relay 140. This circuit extending from ground at contacts 254, conductor 28, the chain circuit through the back contacts of the other line relays, contacts 141, 103 and the lower winding of relay 140 to battery. At contacts 251, relay 250 completes the circuit for energizing the preselected connect relay 280. This circuit extending by way of ground at contacts 237, contacts 251, 276, 276 and the winding of relay 280 to battery. At contacts 252, relay 250 prepares a "kick-off" circuit for shunting the distributor relay 275 to cause it to release in case the linefinder has not located the calling line within the release time of the slow-to-release relay 270. At contacts 253, relay 250 opens the operating circuit of all the line relays. At contacts 255, relay 250 applies a ground potential for marking the tens conductor 24 and the units conductor 22. At contacts 256, relay 250 opens the circuit to the slow to release relay 270.

As the connect relay 280 closes its contacts, it will be noted that only the tens and units relays energized will be the ones whose circuits are completed by way of the marked conductors 22 and 24, and that the finder unit switching relay 240 will only be energized through contacts such as 281 when the finder start relay 260 (instead of 250) applies ground at contacts 261. At contacts 286, relay 280 completes a circuit to the units relay 220. This circuit extending by way of the aforementioned ground and over the marked

conductor 22, contacts 286 and the winding of units relay 220 to battery. At contacts 292, relay 280 completes the circuit to the tens relay 200. This circuit extending by way of the previously mentioned ground and over the marked conductor 24, contacts 292 and the winding of tens relay 200 to battery. At contacts 293, relay 280 completes a circuit between conductors 34 and 35 to maintain the finder distributor relay 275 in its operated position. At contacts 294, relay 280 places a shunt across the line conductors 30 and 31, thereby seizing the associated connector and completing a circuit through the differential relay 300 and line relay 310. The tens relay 200 and units relay 220 each operate their respective sets of contacts and thereby extend the calling line through to the associated connector in an obvious manner.

In operating contacts 311, line relay 310 completes a circuit to the cut-off relay 100, which extends by way of ground at contacts 311, conductor 32, contacts 245, 223, 203, conductor 12 and through the winding of relay 100 to battery. At contacts 312, relay 310 opens conductors 34 and 35, but they are closed at contacts 293. At contacts 313, relay 310 applies a ground potential to the holding conductor 36 which provides the tens relay 200 and units relay 220 with an obvious locking circuit extending through their respective contacts 208 and 225. At contacts 315, relay 310 completes a circuit for hold relay 320, which extends by way of ground at contacts 392, contacts 315 and the winding of relay 320 to battery.

At contacts 101 and 102, cut-off relay 100 further opens the operating circuit of line relay 140. At contacts 103, relay 100 opens the holding circuit for relay 140, allowing it to restore. In restoring contacts 146, relay 140 opens the circuit to start relay 250, which upon restoring opens the circuit to connect relay 280 by way of contacts 251. In restoring contacts 293, relay 280 opens the locking circuit of distributor relay 275. In restoring contacts 279, relay 275 completes an obvious circuit to the reset relay 236. At contacts 238, relay 236 applies ground through the make-before-break contacts actuated by armatures such as 278 and 278' of all the distributor relays such as 275 and 275', for completing an energizing circuit to all distributor relays corresponding to idle finder switches; thus under normal conditions, idle finders are pre-selected for subsequent calling lines. For example: considering that the first finder is idle, a circuit may be traced from ground at contacts 238, normally closed contacts controlled by armature 278', over the conductor 34' to the first finder (not shown) through contacts corresponding to contacts 312 and 322, back over conductor 35' and through the winding of relay 275' to battery for operating distributor relay 275', associated with the first finder, to thereby preselect such finder for use on the next call. Similar distributor relays (not shown) associated with idle finders are operated over similar circuits. It will be evident that distributor relay 275 cannot operate at this time since the first finder is busy and contacts 312 and 322 of its associated connector have opened the operating circuit to relay 275. At make contacts 276' relay 275' prepares the circuit to connect relay 280' of the first finder, at make contacts 277' prepares a "kick-off" circuit for relay 275', at contacts 278' substitutes ground through the associated resistance for holding relay 275' operated when reset relay

70 236 restores, and at contact 279' opens one point

in the chain circuit to relay 236. The operation of any distributor relay opens the chain circuit to restore reset relay 236.

The linefinder tens and units relays 200 and 220 are locked operated during the period that either the line relay 310 or the hold relay 320 are energized. As the connect relay 280 has restored and the former energizing circuit for the relays 310 and 320 is opened, they are maintained energized over the extended closed loop including the calling subscriber's station.

The aforementioned "kick-off" feature will now be explained more in detail. As previously stated, in the event that the linefinder has failed to find the calling line within the release time of the slow-to-release relay 270, this timing feature will function to release the linefinder that failed and select the next idle finder which in turn will attempt to connect with the calling line. In restoring contacts 271, relay 270 completes the "kick-off" circuit. At contacts 272, relay 270 opens the circuit to the start relays 250 and 260. At contacts 273, relay 270 completes the circuit to relay 226, which upon energizing shunts its lower winding at contacts 228, thereby making relay 226 slow-to-release. At contacts 227, relay 226 maintains the "kick-off" circuit for an added interval of time—by way of a second path, after the start relay 250 restores. Assuming that the last finder has failed to connect with the calling line, the "kick-off" circuit may be traced from battery and resistance through contacts 252, contacts 271, 277', 277, 293 and through the winding of distributor relay 275 to battery, thereby shunting out relay 275.

Since distributor relay 275 has both its terminals connected to the negative pole of battery over the above-traced shunt circuit, relay 275 restores. At contacts 276, relay 275 opens the circuit to the connect relay 280, which restores. At make contacts controlled by armature 278, relay 275 opens its own locking circuit, at break contacts controlled by armature 278 prepares its own operating circuit, and at contacts 279 prepares or completes the circuit for reset relay 236, dependent upon the operated or released conditions of the other distributor relays. Connect relay 280 releases and opens its contacts to release the operated tens and units relays 200 and 220 in the last finder, thereby restoring said last finder.

The release of relay 270 opens the circuit of start relay 250 at contacts 272 and also operates relay 226 at contacts 273. Relay 226 closes another point in the "kick-off" shunting circuit at contacts 227 so as to maintain the "kick-off" circuit closed for an interval of time after the start relay 250 restores and opens the original "kick-off" circuit at contacts 252. At contacts 253, start relay 250 restores the original energizing circuit to line relay 140 and all other line relays; at contacts 254 opens the locking circuit to the line relays; at contacts 255 removes the marking potential from the tens and units marking conductors; and at contacts 256 closes the circuit for reenergizing relay 270. Relay 270, at contacts 273, opens the circuit to relay 226 which restores after a short interval of time and at contacts 272 recloses the circuit for reenergizing start relay 250. By this time, sufficient time has elapsed to shunt down distributor relay 275 and release the connect relay 280 so that by the time start relay 250 is reenergized, the connect relay associated with the next idle finder is operated over contacts 251 of start relay 250 and operated contacts of

the distributor relay associated with said next idle finder. The reoperation of start relay 250 also at contacts 255 again applies marking ground through the operated contacts of line relay 140 to mark the tens and units marking conductors so as to operate the corresponding tens and units relays in said next idle finder to complete the connection to the calling line in the same manner as previously described.

10 In case two or more subscribers should initiate calls simultaneously only one of the line relays is held operated over a chain holding circuit while the other line relays are released. For example, it will be assumed that subscribers A and D originate simultaneous calls and therefore line relays 140 and 170 are simultaneously operated. Start relays 250 and 260 are operated through contacts 146 and 177. The operation of either start relay 250 or 260 grounds conductor 28, with the result that the line relay nearest the grounded conductor 28 is the only relay which locks itself through its lower or holding winding. Since line relay 170 is the first relay in the chain locking circuit, this relay at contacts 171 completes its locking circuit, while at contacts 172 the chain locking circuit to subsequent line relays in the chain is opened. Therefore, when either start relay 250 or 260 at contacts 253 or 264 open, the original energizing circuits for the line relays are 20 opened with the result that only the line relay having completed its locking circuit is the only relay (or relay 170 in this case) maintained in operated position. Relay 140, therefore, is restored so that only the tens marking conductor 23 and the units marking conductor 21 are marked through operated contacts 175 and 176 of relay 170.

25 Calls originated after the operation of either start relay 250 or 260 do not operate their corresponding line relays because the operating circuits for such relays are opened at either contacts 253 or 264. Since the line relays are released as soon as the finders connect with the calling lines and operate the corresponding cut-off relays, the start relays are only held operated for a short interval of time with the result that subsequent calls can be completed one after the other in rapid succession.

30 Having described the invention, what is considered new and desired to have protected by Letters Patent will be pointed out in the appended claims.

35 What is claimed is:

40 1. In a telephone system, lines having tens and units digit designations, a line circuit for each line including a line relay, an allotter common to said lines, a first and a second start relay included in said allotter, said first relay common to all said lines whose last digit ends in one through five and said second start relay common to all lines whose last digit ends in six through zero, said lines being arranged into tens line groups, a plurality of marking conductors, said marking conductors being divided into two groups, 45 one group being tens marking conductors and the other group being units marking conductors, each tens marking conductor being individual to a corresponding said tens line group, and each units marking conductor being individual to the lines in all said tens line groups having corresponding units digit number designations, a plurality of linefinders, means responsive to the initiation of a call on one of said lines for operating the corresponding line relay, means responsive to the operation of said line relay for select-

ing said marking conductors corresponding to said calling line and for operating said start relay common to said calling line, means responsive to the operation of said start relay for operating one of said linefinders and for marking said selected marking conductors, and tens and units relays in said one finder operated in response to said marked marking conductors for extending said initiated call.

2. In a telephone system, lines having tens and units digit designations, a line circuit for each line including a line relay, a first and a second start relay, said first relay common to all said lines whose last digit ends in one through five and said second start relay common to all lines whose last digit ends in six through zero, said lines being arranged into tens line groups, a plurality of marking conductors, said marking conductors being divided into two groups, one group being tens marking conductors and the other group being units marking conductors, each tens marking conductor being individual to a corresponding said tens line group, and each units marking conductor being individual to the lines in all said tens line group having corresponding units digit number designations, means responsive to the initiation of a call on one of said lines for operating the corresponding line relay, means responsive to the operation of said line relay for selecting said marking conductors individual to said calling line and for operating said start relay common to said calling line, and means responsive to the operation of said start relay for marking said selected marking conductors.

3. In a telephone system, lines having tens and units digit designations, a line circuit for each line including a line relay, an allotter common to said lines, a first and a second start relay included in said allotter, said first start relay common to all of said lines whose last digit ends in one through five and said second start relay common to all of said lines whose last digit ends in six through zero, means responsive to the initiation of a call on one of said lines for operating the corresponding line relay, means responsive to the operation of said line relay for operating said start relay common to said calling line, a plurality of linefinders, and means responsive to the operation of said start relay to operate one of said linefinders for connecting with said calling line.

4. In a telephone system, lines having tens and units digit designations, a line circuit for each line including a line relay, an allotter common to said lines, a first and a second start relay included in said allotter, said first start relay common to all of said lines whose last digit ends in one through five and said second start relay common to all of said lines whose last digit ends in six through zero, means responsive to the initiation of a call on one of said lines for operating the corresponding line relay, and means responsive to the operation of said line relay for operating said start relay common to said calling line.

5. In a telephone system, lines, a line circuit for each line including a line relay, each of said line relays having a first and a second winding, said first winding providing an operating circuit and said second winding providing a holding circuit for said relays, a chain circuit controllable by all of said line relays, means responsive to the initiation of a call on one of said lines for operating the corresponding line relay over its said first winding, and means responsive to the operation of said line relay for serially including said second winding of said relay in said chain circuit to

maintain said relay operated only in case no other of said line relays are operated.

6. In a telephone system, groups of subscriber lines having tens number designations corresponding to said groups and units number designations corresponding to the location of said lines in said groups, finder switches having tens and units relays for connecting said finders to calling ones of said lines, a line relay individual to each of said lines, means for operating one of said line relays in response to the initiation of a call on one of said lines, tens and units marking conductors, contacts on said one operated relay for marking one of said tens marking conductors corresponding to the tens number designation of said calling line and for marking one of said units conductors corresponding to the units number designation of said calling line, a connect relay individual to one of said finders operated in response to the operation of said line relay, contacts on said operated connect relay for extending the markings on said marked tens and units marking conductors to operate the corresponding tens and units relays in said one finder to complete a connection from said calling line to said one finder, means for releasing said operated line relay in response to the connection of said one finder to said calling line, and means for preventing the operation of a second one of said line relays during the time a preceding one of said line relays is operated.

7. In a telephone system, a plurality of subscriber lines, a line relay individual to each line, a finder switch having access to said lines for completing outgoing calls from said lines, tens and units marking conductors marked in response to the operation of a line relay of a calling one of said lines, tens and units relays in said finder operated over said marked conductors for operating said finder to connect with said calling line, and means including a chain circuit extending through contacts on said line relays in series for preventing simultaneous markings of said marking conductors by two or more of said line relays in case two or more of said line relays are simultaneously operated responsive to the initiation of simultaneous outgoing calls from two or more lines.

8. In a telephone system, a plurality of subscriber lines, a line relay individual to each line, a finder switch having access to said lines for completing outgoing calls from said lines, a plurality of circuits closed by the operation of a line relay of a calling one of said lines for operating said finder switch to connect with said calling line, and means including series of contacts on all said line relays arranged in a chain so that when a plurality of line relays are operated only one will be maintained operated to close said circuits to said finder switch.

9. In a telephone system, a plurality of subscriber lines, a line relay individual to each line, a plurality of finders having access to said lines for completing outgoing calls from said lines, means including automatic switching apparatus for preselecting an idle one of said finders, a plurality of circuits closed by the operation of a line relay of a calling one of said lines for operating said preselected finder to connect with said calling line, and means including series of contacts on all said line relays arranged in a chain so that when a plurality of line relays are operated only one will be maintained operated to close said circuits to said preselected finder.

10. In a telephone system, a plurality of lines,

a line relay individual to each line, a plurality of finder-connector links, tens and units relays in the finder portions of said links for connecting calling ones of said lines to the associated connector portions of said link, means for preselecting an idle one of said finder-connector links for use, means effective when a call is initiated over one of said lines for operating the corresponding one of said line relays, a certain tens relay and a certain units relay in said preselected finder connector link operated in response to the operation of said one line relay for connecting said calling line through said finder portion to said connector portion of said preselected link, means for releasing said one line relay in response to the extension of said calling line to said connector portion of said preselected finder-connector link, and means for preventing the operation of any other line relays after said one line relay has been operated, until after said one line relay has been released.

11. In a telephone system, a plurality of lines, a line relay individual to each line, a finder terminating a trunk, tens and units relays in said finder for connecting calling ones of said lines to said finder, means effective when a call is initiated over one of said lines for operating the corresponding one and of said line relays, a certain tens relay and a certain units relay in said finder operated in response to the operation of said one line relay for connecting said calling line through said finder to said trunk, means for releasing said one line relay responsive to said connection of said calling line to said trunk, and means for preventing the operation of any other line relays after said one line relay has been operated, until after said calling line is connected through said finder to said trunk and said one line relay has been released.

12. In a telephone system, a plurality of lines, a line relay individual to each line, a start relay common to said lines, normally closed contacts on said start relay, normally open contacts on said start relay, an individual operating circuit including the line conductors of said line and said normally closed contacts on said common start relay for each of said line relays, means for operating any one of said line relays over its individual operating circuit, normally open contacts on each of said line relays for operating said common start relay in response to the operation of any one of said line relays, and a holding circuit for each line relay including a locking contact on each line relay and said normally open contacts on said common start relay.
13. In a telephone system, a plurality of lines, a line relay individual to each line, a start relay common to said lines, normally closed contacts on said start relay, normally open contacts on said start relay, an individual operating circuit including the line conductors of said line and said normally closed contacts on said common start relay for each of said line relays, means for operating any one of said line relays over its individual operating circuit, normally open contacts on each of said line relays for operating said common start relay in response to the operation of any one of said line relays, and a holding circuit including said normally open contacts on said common start relay and a chain circuit progressively extending through contacts on said line relays in series for maintaining only one of said line relays in operated position at a time.
